[57] CLAIM

The ornamental design for a lamp-bulb-receptive socket portion of a molded-plastic vehicle lamp assembly, as shown and described.

DESCRIPTION

FIG. 1 is a front and upper left perspective view of a lamp-bulb-receptive socket portion of a molded-plastic vehicle lamp assembly showing our new design, the rear wall of the socket, shown in section, being a fragment of the complete lamp assembly. The broken line illustrations of portions of the lamp housing structure are included for the purpose of illustrating environmental elements that form no part of the claimed design; FIG. 2 is a front elevational view thereof; FIG. 3 is a right side elevational view thereof, the left side elevational view thereof being a mirror image and the rear wall of the socket, shown in section, being a fragment of the complete lamp assembly; FIG. 4 is a bottom plan view thereof; FIG. 5 is a cross-sectional view thereof taken along line 5—5 of FIG. 2; and, FIG. 6 is a cross-sectional view thereof taken along line 6—6 of FIG. 4.
